(57) **CLAIM**

The ornamental design for a device for facilitating placement of a case on a pillow, as shown and described.

DESCRIPTION

FIG. 1 is a perspective view of the device for facilitating placement of a case on a pillow showing my new design;

FIG. 2 is an alternative perspective view thereof;

FIG. 3 is a front plan view thereof;

FIG. 4 is an alternative front plan view thereof;

FIG. 5 is a top plan view thereof;

FIG. 6 is a bottom plan view thereof;

FIG. 7 is a right side elevation view thereof;

FIG. 8 is a left side elevation view thereof;

FIG. 9 is a perspective view of the device for facilitating placement of case on a pillow depicting the device covering the pillow;

FIG. 10 is a front plan view thereof;

FIG. 11 is an alternative front plan view thereof;

FIG. 12 is a top plan view thereof;

FIG. 13 is a bottom plan view thereof;

FIG. 14 is a right side elevation view thereof; and,

FIG. 15 is a left side elevation view thereof.

The portions shown in broken lines form no part of the claimed design.
